United States Patent Office

Des. 212,382
Patented Oct. 8, 1968

212,382

LIGHTER

Albertus van Poppel, Asserstraat 11,
Rolle, Netherlands

Filed Dec. 1, 1967, Ser. No. 9,605

Term of patent 3½ years

(Cl. D48—27)

FIG. 2

FIG. 3

FIG. 1

I claim:

The ornamental design for a lighter, as shown.
